Des. 182,367
Patented Mar. 25, 1958

182,367

COMBINATION TRASH AND GARBAGE UNIT

Earl J. La Pan, Miami, Fla.

Application July 30, 1956, Serial No. 42,452

Term of patent 14 years

(Cl. D58—17)

FIG. 1

FIG. 2

FIG. 3

FIG. 4

FIG. 6

FIG. 5

FIG. 7

Figure 1 is a front elevational view of a combination trash and garbage unit showing my new design.

Figure 2 is a side elevational view thereof;

Figure 3 is a rear elevational view thereof;

Figure 4 is a top plan view thereof;

Figure 5 is a bottom plan view thereof;

Figures 6 and 7 are perspective views thereof showing its rear door and front cover respectively in partially open positions.

I claim:

The ornamental design for a combination trash and garbage unit, substantially as shown.
